UNITED STATES PATENT OFFICE.

SAMUEL W. RAYMOND, OF ADRIAN, MICHIGAN.

DESIGN FOR A SERVICE-STATION.

51,322.

Specification for Design.

Patented Oct. 2, 1917.

Application filed July 9, 1917. Serial No. 179,561. Term of patent 14 years.

To all whom it may concern:

Be it known that I, **SAMUEL W. RAYMOND**, a citizen of the United States, residing at Adrian, in the county of Lenawee, State of Michigan, have invented a new, original, and ornamental Design for a Service-Station, of which the following is a specification, reference being had to the accompanying drawing, forming part thereof.

The figure is a perspective view of a service station, showing my new design.

I claim:

The ornamental design for a service station, as shown.

SAMUEL W. RAYMOND.

Witnesses:

KARL H. BUTLER,
ANNA M. DORR.
